UNITED STATES PATENT OFFICE

MARSHALL C. HJELTE, OF HONOLULU, TERRITORY OF HAWAII, ASSIGNOR TO
HAWAIIAN PINEAPPLE COMPANY, LIMITED, OF HONOLULU, HAWAII, A CORPO-
RATION OF HAWAII

SLICING MACHINE

Application filed August 6, 1931. Serial No. 555,585.

The invention relates to certain improvements in slicing machines of the general character of that shown in Patent No. 1,519,158, December 16, 1924, and has for its object to provide such a machine with means for delivering the sliced articles from the machine with the slices thereof in parallel facial abutment, thereby facilitating the packing of the sliced articles in substantially the same shape in which they were fed to the machine, said improvements also including means for actuating the mechanism feeding the articles to the cutting or slicing mechanism at substantially the same rate of speed as that in which the discharge belt or packing conveyor is operated, so that there is no tendency of the slices becoming separated due to changes in speed of travel thereof; the improved machine also including the disposition of the main elements of the driving mechanism below the slicing apparatus and enclosed within a suitable casing associated with the supporting frame, whereby the driving mechanism will be protected, but will, nevertheless, be readily accessible for adjustment and repair.

The invention is illustrated in the accompanying drawings, in which:—

Fig. 1 is a side elevation of the machine.

Fig. 2 is a plan view thereof.

Fig. 3 is a detail view of the intermittently operated feed conveyor.

Fig. 4 is a fragmentary sectional elevation on an enlarged scale.

Fig. 5 is an enlarged detail of one of the supporting brackets for the feed chain.

Fig. 6 is a similar view of the companion bracket showing the relation of the feed chain to the discharge member.

Fig. 7 is a sectional elevation of part of the driving mechanism.

Fig. 8 is a perspective view of the tubular discharge member.

Fig. 9 is a horizontal section through the main gear casing.

Fig. 10 is a section on line 10—10 of Fig. 9.

Referring to the drawings, 1 indicates the frame or standard of the machine provided with an upper frame section 2, which latter carries the slicing mechanism, the intermit-

tent feed chain associated therewith and the tubular discharge member.

Supported on a suitable bracket 3 attached to the main frame 1 is an electric motor 4 for operating the machine, said motor driving the main shaft 6 of the machine through chain and sprocket gearing 5, 5', the sprocket 5 being adapted to be coupled and uncoupled with respect to the main shaft by a clutch 7 of any appropriate form. The main shaft 6 is mounted in a bearing in a gear casing 1' preferably formed as an integral part of the main frame 1. Fast to the inner end of the shaft 6 is a pinion 10 meshing with gear 11 on countershaft 12, which latter carries a pinion 13 meshing with gear 14 on a second countershaft 15, said shaft having secured thereto a spiral gear 30 and carrying on one end the sprocket 16 and on the opposite end sprockets 80 and 91.

The sprocket 16 drives through chain 17, two sprockets 21, 21' mounted on vertically spaced shafts 19 and 20, which shafts carry the driving drums 22, 22', which operate the discharge conveyor or packing belt 23.

The spiral gear 30 meshes with a spiral gear 31 fast to a vertical shaft 32 journaled in bearings in a generally cylindrical section of the gear casing. Fast to the shaft 32 is an intermittent motion driving gear 34 having helical teeth on half of its periphery and a single circumferential tooth or rib on the other half, said gear meshing with a helical driven gear 35 on countershaft 35', on the outboard end of which is secured a sprocket 36. The vertical shaft 32 is provided at its top with a bevel gear 40, which meshes with a similar gear 41 on shaft 43 journaled in bearings formed in the top frame section 2, said shaft 43 carrying a rotary cutter 44 of the same general type as illustrated in the patent aforesaid, which cutter cooperates with a slotted tubular head 45 also similar to that employed in the machine of said patent, the relation of the cutter and head being such that the cutter rotates continuously, the knives traversing the slots in the head during half of each revolution of the cutter and cutting the fruit or other article, held stationary within the tubular head, into uniform slices.

As in the machine of the patent aforesaid, the articles to be sliced are delivered intermittently to the interior of the head 45 where they are held stationary during the slicing operation, the intermittent feeding of the articles and the discharge of the same from the head, after slicing, being effected by a feed chain of the same general type as that illustrated in the said patent, special provision being made to drive the chain during its movement at the same rate of speed as that of the delivery belt or conveyor 23. The feed chain 62 is provided with pusher arms 63 spaced at regular intervals and serving to move the articles to be sliced from the preliminary feed trough 46 into the slotted tubular head 45. The chain 62 is guided by sprocket 60 carried by a stud mounted on bracket 59, a sprocket 61 carried by the upper frame section 2 and a tensioning sprocket 54 carried by an adjustable support 52 mounted on a bracket 50 also carried by the upper portion of the frame. The chain is driven by a sprocket 55 provided with a number of teeth equal to the number of links in each section of the chain between the pusher arms 63 carried by said chain, so that one revolution of the sprocket 55 moves the chain through a distance equal to that between two successive pusher arms 63.

The shaft 56 bearing sprocket 55 is driven by chain 58 engaging sprocket 57 thereon, said chain being, in turn, driven by the sprocket 36 on the countershaft 35', which is intermittently operated by the timing gear consisting of the helical driven gear 35 and the driving gear 34, one-half of the periphery of which is provided with helical teeth and the other half with a circumferential rib or single tooth, as hereinbefore explained, this arrangement constituting a timing gear for intermittently driving the sprocket 55 through one complete revolution and this particular gear train is so proportioned that the speed of the chain 62 is the same as that of the discharge or packing belt 23. The helical teeth on the periphery of gear 35 are interrupted at each 120° of the circumference by a transverse channel, which is engaged by the rib or peripheral tooth on the gear 34, so that said gear 35 makes three start-stop movements in each complete revolution and, as the ratio of the sprockets 36 and 57 is three to one, a complete revolution of the sprockets 57 and 55 is effected for each start-stop movement of the shaft 35', which corresponds to a complete revolution of the shaft 32 and a complete revolution of the knife shaft.

Secured to the upper frame member and in alignment with the longitudinal axis of the slotted head 45 is a discharge member comprising a tubular section 70 provided with a slot 71 aligning with the corresponding slot in the head 45 to permit the passage of the shanks of the pusher arms 63, the

interior diameter of the tubular member 70 being substantially equal to that of the slices into which the article is cut, and telescopically engaging the tubular member 70 is a tubular extension 72 provided with a longitudinal slot 73 aligning with slot 71 and also having a slot 74 substantially diametrically opposite the slot 73 to provide a certain amount of spring tension in the outer end of the member 72, which end is tapered or reduced to a small extent, so that the interior diameter of said tubular member at the outer end is somewhat less than the diameter of the cut slices and, as the latter are forced into the tubular end by the pusher arms, the slices will be forced into facial abutment and the sliced article will be delivered to the discharge conveyor or packing belt 23 in substantially the same form in which it was delivered to the machine, that is to say, the sliced article will be received on the packing belt with all of the slices in upright abutting relation, so that the entire sliced article may be readily packed in suitable containers.

On shaft 15 is mounted sprocket 80 driving through chain 81 to sprocket 82 mounted on shaft 83. On shaft 83 is mounted head sprocket 84 driving feed conveyor chain 86 provided with flights 87. As indicated in Figs. 1 and 4, the feed conveyor 86 delivers the trimmed articles, such as pineapples or the like, to a trough 46 mounted in axial alignment with the tubular head 45, the said articles being successively engaged by the pusher arms 63 of the feed chain 62, as said articles are disengaged from the feed conveyor, the relation of the parts being more particularly illustrated in Fig. 4. Each article, as it is engaged by a pusher arm 63, is advanced into the slotted head 45 and, when the engaging pusher arm 63 reaches the forward end of the head, the movement of the feed chain 62 is arrested by the peripheral single toothed section of the gear 34 passing into mesh with the spiral gear 35, thereby stopping the rotation of shaft 35', which is connected to the drive shaft of the feed chain 62, as hereinbefore explained. The article to be sliced is, therefore, held stationary in the head and, while so held, the knives carried by the rotary cutter 44 traverse the slots in the head 45 and cut the article into uniform slices, after which the knives pass out of engagement with the slots and the helical teeth on gear 34 pass into mesh with spiral gear 35 and the latter again resumes its function of driving the feed chain 62 for a distance equal to one complete revolution of sprocket 55 or the space between successive pusher arms 63. The renewed movement of the feed chain 62 causes the pusher arm in contact with the slices to move the latter out of the head into the tubular discharge member and, by reason of the resistance of the tapered outer end of the discharge member,

forces the slices into facial engagement, so that the slices will be delivered onto the conveyor belt 23 in compact form and may be taken from the belt in such form and packed in suitable containers.

5 It will be noted that the speed of the feed conveyor 86 is regulated to agree with the speed of the discharge conveyor or packing belt 23 and also with the intermittent speed of the feed chain 62, so that the travel of the 10 articles through the machine will be properly timed and this timing, when correlated with the tubular discharge member with its tapered and resilient outer end, insures the delivery of each sliced article in compact 15 form with the slices in facial abutment, so that the entire article may be delivered directly to the cans or similar containers for subsequent processing.

20 Preferably, the machine is associated with the trimming table where the pineapples or other articles to be sliced are inspected and prepared for slicing. This trimming table consists principally of two conveyors; one, 25 a slow moving belt which carries the sized pineapples to the trimmers; the other, a chain conveyor, 86, with flights, as described above, which carries the trimmed pineapples to the slicing machine. To this end, shaft 15 is 30 provided with a second sprocket 91, which is engaged by chain 92 driving a relatively large sprocket 90 fast to a sleeve 93 loosely mounted on the shaft 83, to which sleeve is secured a driving pulley 94, which operates the feed 35 belt of the trimming table.

35 What I claim is:

1. A slicing machine including a slotted tubular head, a rotary cutter having knives traversing the slots in the head, a feed chain having lateral arms adapted to traverse said head longitudinally, and a resilient outwardly tapering tubular discharge member in alignment with said head traversed by said arms and adapted to deliver the slices in facially abutting series.

40 2. A slicing machine including a slotted tubular head, a rotary cutter having knives traversing the slots in the head, a feed chain having lateral arms adapted to traverse said head longitudinally, a conveyor belt adjacent the end of the head, and a resilient tubular discharge member interposed between the head and the conveyor and traversed by said arms to deliver the slices in parallel facial 45 abutment to the conveyor.

50 3. A slicing machine including a slotted tubular head, a rotary cutter having knives traversing the slots in the head, a feed chain having lateral arms adapted to traverse said head longitudinally, a conveyor belt adjacent the end of the head, a resilient tubular discharge member interposed between the head and the conveyor and traversed by 55 said arms to deliver the slices in parallel facial abutment to the conveyor, and means for

driving the feed chain and conveyor belt at the same rate of speed.

4. A slicing machine including means for cutting fruit and the like into disks, means for moving the articles through and beyond the cutting means, and a tubular discharge member traversed by the moving means and having a contracted end imposing resistance to the movement of the disks; whereby said disks will be discharged in facially abutting series.

In testimony whereof I affix my signature.

MARSHALL C. HJELTE.
